MAILBOX

Lena W. Baker, Fort Worth, Tex.

Application July 5, 1946, Serial No. 681,498

8 Claims. (Cl. 232—19)

1

This invention relates to new and useful improvements in mail boxes.

Many houses and other buildings are constructed without porches or canopies over their entrances and since a mail box is usually installed in the wall adjacent the entrance it is thus exposed to rain and snow, and in many instances even though a canopy overhangs the entrance, it does not protect the mail box from the weather. Consequently when mail is delivered to and collected from such a box, it is likely to be damaged by the elements. Therefore it is one object of my invention to provide an improved mail box which will to a major extent overcome these difficulties and efficiently protect the mail.

A particular object of the invention is to provide a mail box including a chute adapted to be installed in an exterior building wall having means at its lower end for receiving delivered mail and interior and exterior openings at its upper portion; together with an outer door carrying a receptacle on its inner side for holding mail and extending across the chute when the door is closed and swinging outwardly with the door, when the latter is opened.

A further object of the invention is to provide a mail box having a swinging exterior door carrying a receptacle on its inner side having a closed top and rear and end openings, whereby mail placed in said receptacle, when the door is swung open, is protected from the weather.

Another object of the invention is to provide an improved mail box including a chute adapted to be installed in an exterior building wall and having upper and lower interior openings and an upper exterior opening, together with doors covering said openings; the exterior door carrying a receptacle on its inner side accessible from the upper interior opening when the exterior door is closed.

Another object of the invention is to provide an improved mail box which is free from complex operating elements, is simple and compact in construction and which may be made entirely of sheet metal.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is an elevation of a mail box constructed

2

in accordance with the invention, facing the interior side,

Fig. 2 is a transverse vertical sectional view of said box installed in a building wall,

Fig. 3 is an isometrical view of the upper portion of said mail box, the exterior door being open,

Fig. 4 is a horizontal, cross-sectional view taken on the line 4—4 of Fig. 1,

Fig. 5 is an isometrical view illustrating a mail-receiving basket at the lower end of the mail box,

Fig. 6 is a vertical sectional view of the hinged trap plate and a portion of the chute, and

Fig. 7 is a similar view of a modified form of trap plate, on a reduced scale.

In the drawings, the numeral 10 designates an upright chute which includes a top section A, a medial section B and a bottom section C.

20 The chute is preferably formed of sheet metal which may be galvanized or otherwise weather-proofed. This chute may have a generally rectangular shape in cross-section, having its greater dimension from end to end. The lower end of 25 the top section A is reduced and shouldered, as indicated at 11, to telescope the upper end of the section B and rest thereon. The lower end of the section B is also reduced and shouldered, as indicated at 12, to telescope the top of the section C.

The medial section B is provided at its ends with projecting ears 13 which are secured to the end walls of the sections A and C by rivets or bolts 14. In Fig. 2, the chute is shown mounted 35 in an exterior building wall between the outer covering 15, which may be brick, wooden or cement, and the inner covering 16, which may be of any suitable structure. For the purposes of description, the covering 15 will be referred to as the outer or exterior wall; while the inner covering 16 will be called the inner wall. By making the chute in sections it lends itself to adjustability and variation in dimensions. While 40 the sections are shown as each engaging both walls, this is not essential and the design may be altered in accordance with building conditions.

The bottom section C has a closed bottom 17 and a false bottom 18 inclining toward a transverse receiving opening 20 in its inner wall 21; said opening extending from one end wall to the other end wall of the section. Mail, such as packages, dropped into the chute is accumulated 50 on the inclined bottom 18. An outwardly-di-

rected collar 22 surrounds the opening 20 and fits in an opening 23 in the inner wall 16.

An elongate hinge sleeve 24 is formed on the medial portion of the outer edge of the collar and lies between similar sleeves 25 formed on the upper edge of an elongate door 26; said sleeve being hinged on a pintle 27. The door overhangs the collar and the opening 23 and is provided at its lower end with a central knob 26'. Any suitable catch may be provided for holding the door in a closed position and preventing mail parcels from pushing it open. If desired, a receiving basket 28 having a hanger yoke at its rear side, may be used, as is shown in Fig. 5. A pair of hooks 29 may be inserted in the wall 16 above the opening 23. When the basket is employed, the door 26 is swung up against the inner wall and yoke engaged on the hooks in front of the upturned door, whereby said door is supported. The rear of the basket is open and its bottom will be below the opening 23 so that mail falling upon the inclined bottom 18, will slide down into said basket.

The top section A has a closed top 30 and an interior opening 31 in its inner wall surrounded by a rectangular collar 32, extending horizontally of the section. An inner door 33 is hinged at one end to the collar and is indicated at 34. At its opposite end the door has a knob 35 and any suitable catch (not shown) may be used. The collar 32 fits snugly in an opening 36 in the wall 16. The doors 26 and 33 overlie the openings 23 and 36 flat against the surface of the inner wall 16, thus concealing said openings and the collars 22 and 32.

As is best shown in Figs. 2 and 3, the section A has an elongate rectangular opening 37 across its front wall which fits snugly in an opening 39 in the outer wall 15. The top 30 is extended to form the top of the collar. An elongate face plate 40 is secured longitudinally across the outer edge of the top 30, extending above and below said top. An elongate hood 41 secured to the upper portion of the face plate overhangs the collar and protects the opening into the chute. An elongate exterior door 42 hinged to one end of the collar at 43, has its upper edge underlying the bottom edge of the face plate, when closed. This door overlies the ends and bottom of the collar and rests flat against the outer face of the wall 15, when closed.

A very important feature of the invention resides in an elongate receptacle 44 suitably secured to the inner side of the door, as by welding, whereby the door forms the front thereof. This receptacle has a closed top 45 and its hinged end is closed by an end wall 46. When the door is swung outwardly, the receptacle is likewise swung outwardly through the collar to the position shown in Fig. 3 and the top 45 protects the interior of said receptacle. When the door is closed the receptacle extends across the chute to the opening 31.

It will be observed that the collar 38 has a greater vertical height than the collar 32. The bottom 47 of the receptacle is stepped so that its outer portion overlies the bottom of the collar 38 and its inner portion is flush with the bottom of the inner collar 32 and close thereto. The reduced rear or inner side of the receptacle is open, as indicated at 48, so that when the inner door 33 is opened access is readily had to said receptacle to place mail therein or remove it therefrom.

The outer end of the receptacle is cut at such an angle to the door 42 as to cause the outer end to clear the collar when the door is swung. In

order that the mailman may remove mail from or deposit mail in the receptacle, an opening 49 is provided in the outer end wall thereof. The receptacle is long enough to accommodate letters, 5 papers and magazines, but may be of less length.

An inclined trap plate 50 is hinged to the outer wall of the section A just below the collar 38 and inclines down into the section B, with its lower edge in engagement with the inner wall thereof. 10 In order to support this plate in position and to return it to such position, when it is depressed and released, it is provided with a spring hinge 51 mounted on the outer wall of the section A (Figs. 2 and 6). In Fig. 7, a modified form of trap plate is shown. A trap plate 52 formed of 15 spring metal is bent at its upper edge to form a downturned flange 53 which is secured to the outer wall of the section and the lower edge portion of said plate is curved downwardly to rest against the inner wall of the section B. In either form, a package or parcel dropped on said plate will depress the latter and fall to the inclined bottom 18, thus being trapped below the plate which will return to normal position. The exterior door 42 is provided with a knob 54 connected with a suitable catch 55, which may be of the lock type if desired.

When the mail box is installed in the building wall, the parts will be in the positions shown in 30 Fig. 2. The exterior door 42 being closed, rain or snow cannot enter the opening 37 through the collar 38 and of course the top 45 keeps water out of the receptacle 44. The hood 41 deflects water running down the outer surface of the 35 wall 15 and from blowing in between the face plate 40 and the top of said receptacle. Since the door 42 overlies the bottom and vertical edges of the collar 38, the opening 39 is protected.

In using the mail box, the occupant of the 40 building may place letters and other mail matter in the receptacle by opening the door 33, which gives access to said receptacle through the opening 48. In delivering mail the postman swings the door 42 open to the position shown in Fig. 3 and removes any mail therefrom which is to be posted. The door 33 being closed and the trap plate 50 being up, cold air is substantially precluded from entering the building. Letters and 45 suitable mail are deposited by the postman in the receptacle through the end opening 49 and are thus protected from the weather. Large packages and parcels are inserted through the collar 38 and dropped on the plate 50 which will swing downward and drop said mail onto the inclined bottom 18. If the door 26 is closed the mail will be held in the bottom of the chute, but if the basket 28 is used, as shown in Fig. 5, then the mail will slide out into said basket.

The postman closes the door 42 and latches it. To remove mail the occupant opens the doors 32 and 26 and the mail is received in good condition. If the postman should have only letters or small parcels to deliver it is obvious that the door 42 need not be fully opened. If the door is swung outwardly only sufficiently to expose the front end of the opening 49, the top 45 in conjunction with the hood 41 will protect the opening 37 and exclude the elements.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A mail box including, an upright chute adapted to be mounted in an exterior wall of a building and having means at its lower end for receiving delivered mail and an interior opening and an exterior opening at its upper portion, an exterior door closing the exterior opening of the chute, and a receptacle for mail carried by the door extending into the chute when said door is closed and swinging outwardly with the door when said door is opened.

2. A mail box including, an upright chute adapted to be mounted in an exterior wall of a building and having means at its lower end for receiving delivered mail and an interior opening and an exterior opening at its upper portion, an exterior door closing the exterior opening of the chute, and a receptacle for mail carried by the door extending into the chute when said door is closed and swinging outwardly with the door when said door is opened, the receptacle having an opening accessible from the interior opening of the chute when the door is closed.

3. A mail box including, an upright chute adapted to be mounted in an exterior wall of a building and having means at its lower end for receiving delivered mail and an interior opening and an exterior opening at its upper portion, an exterior door closing the exterior opening of the chute, and a receptacle for mail carried by the door extending into the chute when said door is closed and swinging outwardly with the door when said door is opened, the receptacle having an opening accessible from the interior opening of the chute when the door is closed and a second opening accessible when the door is open.

4. A mail box including, an upright chute adapted to be mounted in an exterior wall of a building and having means at its lower end for receiving delivered mail and interior and exterior openings at its upper portion, an exterior door closing the exterior opening of the chute, and a receptacle carried by the inner side of the door having its top closed and having openings in its rear side and one end.

5. A mail box including, an upright chute adapted to be mounted in an exterior wall of a building and having means at its lower end for receiving delivered mail and an interior opening and an exterior opening at its upper portion, an exterior door closing the exterior opening of the chute, and a receptacle carried by the inner side of the door having its top closed and having openings in its rear side and one end, the opening in the rear side of the receptacle communicating with the interior opening of the

chute when the door is closed and the opening in the end of the chute being exposed when the door is opened.

5 6. A mail box including, a box section adapted to be mounted in an exterior building wall having an interior opening in its inner wall and an exterior opening in its outer wall, a door hinged on the section at one end of the exterior opening thereof, and an elongate receptacle mounted on the inner side of the door and extending across the section to the interior opening when the door is closed and movable outwardly through the exterior opening of the receptacle when the door is swung open, the receptacle having a fixed and sealed top, whereby rain and snow are excluded from the receptacle when said receptacle is swung outwardly with the door and mail is deposited in the receptacle.

10 7. A mail box including, an upright chute adapted to be mounted in an exterior wall of a building and having means at its lower end for receiving delivered mail and an interior opening and an exterior opening at its upper portion, an exterior door closing the exterior opening of the chute, a receptacle for mail having a closed top, said receptacle and said top being carried by the door and extending into the chute when said door is closed and swinging outwardly with the door when said door is opened, and a trap plate hinged in the chute between the upper and lower openings.

15 8. A mail box including, an upright chute having a separate medial section attached to a separate bottom section and a separate top section attached to the medial section, the bottom chute section having an interior opening and a door therefor, the top section having interior and exterior openings, an inner door for the interior opening of the top section, an exterior door for the exterior opening of the top section, and a receptacle secured to the inner side of the exterior door and extending across the top section to the interior opening thereof, said receptacle having a closed top and openings in 45 its rear side and one end.
